BERTH

Roger G. Cudini, Birmingham, Mich., assignor to
Moynahan Bronze Company, Detroit, Mich., a
corporation of Michigan

Application February 15, 1949, Serial No. 76,509

7 Claims. (Cl. 5—10)

1

This invention relates to berth structures and more particularly to suspension mechanism for vertically shiftable berth structures.

In one type of vertically adjustable berth structure for railroad cars, and other uses when there is limited room dimensions, the lower ends of suspension cables are attached to the berth pan and the upper ends of the cables are fastened to spring controlled anchorage means located in the region of the roof or ceiling. Such anchorage means usually includes a movable head controlled by springs housed in a container. As such anchorage means is generally bulky, considerable head space is sacrificed for its accommodation, particularly where it is concealed from the room by the ceiling, and maximum effort is required for attachment, detachment and when servicing.

An object of this invention is to provide a vertically adjustable berth structure that is suspended so that it can be readily attached or detached in a room of restricted dimensions.

A further object of the invention is to provide a vertically adjustable berth structure in which the spring controlled cable anchor means is located in the berth pan whereby there will be maximum head space in the room when the berth is stored in its upper position.

Another object of the invention is to provide an assembled or package vertically adjustable berth structure in which the spring controlled anchorage means for suspension cables is carried in the berth pan so that the upper ends of the cables can be readily applied to or removed from fixed anchor brackets when the berth structure is being installed or removed for service.

These and other objects of the invention will be apparent to those skilled in the art from a study of the following description and accompanying drawings, in which:

Figure 1 is a vertical sectional view of a sleeping car room having the berth structure installed therein.

Figure 2 is a sectional view of the berth structure taken on line 2—2 of Figure 4.

Figure 3 is a fragmentary perspective view of a cable pulley structure at one corner of the berth pan.

Figure 4 is a top plane view of the berth structure taken on line 4—4 of Figure 1, parts being broken away to show underlying parts.

2

Figure 5 is a sectional view of the berth structure taken on line 5—5 of Figure 4.

A bedroom 10 of limited dimensions, such as contained in a sleeping car 11 for railroads, is formed by flooring 12, ceiling 13, end walls 14 and side walls of which the outer wall 15 is shown in the drawings. In the room is a seat structure 16 having a hinged back 17 that may be of the type carrying a berth.

10 Within the room is a berth structure of which the rectangular pan 18 is substantially the same length as the room. If desired, the pan may be slidably guided on the walls of the room in a conventional manner, but such guide means is 15 not shown as it forms no part of the invention.

The pan 10 of the berth structure comprises a marginal wall preferably formed of extruded metal sections 19 welded together at their adjacent ends. These wall sections have an inturned bottom flange 20 and an inwardly extending intermediate flange 21 above the bottom flange. Sheet metal bottom wall 22 underlies and is welded to, or otherwise suitably fixed against the under face of the bottom flanges. Sheet metal 25 false bottom 23 is secured on top of the flanges 21 by detachable means, such as screws 24.

Walls 19, bottom cover 22 and cover 23 define a closed chamber 25 into which suspension cables 26 extend and are movably anchored. The ends 30 of the cables in the chamber are attached to movable anchor means or a carrier having a head 27 provided with openings 28 through which the cable ends extend. The cables extend through the head and their projecting ends are secured to 35 nut 29. Guide shoe 30 depends from the head and is mounted to ride in guide channel 31 extending lengthwise of the pan. Under the guide channel is arranged a sheet 32 formed of sound deadening material, which is secured to the pan 40 bottom by rivets 34 and by rivets 33 that also secure the guide channel to the pan bottom. Sheet 32 also serves to stiffen the pan bottom.

Wings 35 project from the sides of the 45 slideable anchor head above the guide channel and are provided with holes for receiving and anchoring one end of tension coil springs 36 which are preferably coated with sound deadening material. The other ends of such tension springs are secured to bracket 37 fixed to one of the end walls 50 of the pan between bottom 22 and false bottom 23.

Similar cable guiding units are provided at each corner of the pan and they each comprise a single pulley 38, pin 39 on which the pulley is mounted, arms 40, angular bracket 41 and tube 42. The brackets fit into the corners of the pan frame and are welded thereto and the tubes are welded within and to the corner portion of the brackets. Arms 40 are welded to the lower ends of the brackets and tubes and extend downwardly at an angle through false bottom 23 so that the pulleys 38 lie within chamber 25.

Another cable guiding unit is provided in chamber 25 and is located between the corner pulleys and the anchor head. This unit comprises a bracket 44, suitably secured to the bottom and end wall of the pan within chamber 25, carrying pins 45 on which double pulleys 46 are mounted. The cables extend through tubes 42 and around pulleys 38 and 46 within the chamber 25. The upper ends of the cables are attached to suitable anchors 46, such as eyescrews, fixed to the room ceiling 13.

Springs 36 will normally maintain the slidable guided anchor head 35 in the position shown in dotted lines in Figure 4 whereby the cables will be drawn into the chamber 25 a maximum extent to locate the berth pan in its upper vertical position adjacent the ceiling of the room. The berth pan is moved downwardly to prone position in opposition to the force exerted by the tension springs and suitable latch means (not shown) may be provided to retain the berth structure in such position. Upon the breakage of one of springs 36, the guide shoe 30 will cock and wedge in the guideway making it impossible to move the carrier head, and the operator will thus know when such a condition is encountered.

It will be noted that the spring controlled anchorage portion of the suspension means is enclosed in the berth pan chamber 25 and thus no head space is required to house such mechanism. Further, the arrangement of the spring controlled anchorage within the pan permits assembly and repair at a station remote from the room ceiling whereby obviating inaccessibility difficulty.

The invention may be modified in various respects as will occur to those skilled in the art and the exclusive use of all modifications as come within the scope of the appended claims is contemplated.

What is claimed is:

1. A bed structure adapted to be lowered from the ceiling of a bedroom for occupancy comprising a berth pan having a bottom chamber, a plurality of pan suspension cables having their lower ends extending into the pan chamber and their upper ends adapted to be anchored to the bedroom ceiling, slidably mounted anchor means in the pan chamber to which the lower ends of the cables are attached, and spring means in the chamber connected to the pan and the slidably mounted anchor means, said spring means exerting a force upon the slidable anchor means in a direction tending to take up the cables.

2. A bed structure adapted to be lowered from adjacent the ceiling of a bedroom for occupancy comprising a rectangular pan, a plurality of cables for suspending the berth pan in horizontal position in the bedroom, the upper ends of said cables being adapted to be secured to the bedroom ceiling, a guideway member secured to the bottom of the pan, an anchor member having a shoe portion slidably mounted in the guideway member, the lower ends of the cables being attached to said slidable anchor member, and tension springs

secured to the anchor member and the pan, said springs exerting a force upon the slidable anchor member in a direction tending to take up the cables.

3. A bed structure adapted to be moved vertically toward and from the ceiling of a bedroom comprising a rectangular pan having a false bottom forming a lower chamber therein, a strip of reinforcing sound dampening material secured on the bottom of the pan within the chamber, a guideway fixed on the strip, an anchor member having a shoe slidably mounted in the guideway, tension springs having one end connected with the pan and the other end connected with the anchor member, pulleys fixed in the chamber at the corners of the pan, and supporting cables having their upper ends adapted to be anchored to the bedroom ceiling and their lower ends extending into the pan chamber over the pulleys and secured to the anchor member, said springs exerting a force upon the slidable anchor member in a direction tending to take up the cables.

4. A bed structure adapted to be lowered from the ceiling of a bedroom for occupancy comprising a rectangular pan having a closed bottom chamber, guide pulleys in the chamber adjacent the corners of the pan, a plurality of cables having their upper ends adapted to be anchored to the bedroom ceiling, a slidably mounted carrier in the chamber to which the lower ends of the cables are secured, a guide pulley for the cables secured in the chamber in line with the carrier, and a plurality of tension coil springs connected with the pan and the carrier to exert a force upon the carrier in a direction tending to take up the cables.

5. A bed structure adapted to be lowered from the ceiling of a bedroom for occupancy comprising a rectangular pan having a bottom and a removable false bottom defining a lower chamber, a carrier slidably mounted in the chamber, a bracket in the chamber fixed to the pan in line with the carrier, a double pulley mounted on the bracket, pulleys in the chamber secured to the corner portions of the pan, suspension cables having their upper ends adapted to be anchored to the bedroom ceiling and their lower ends passing over the corner and double pulleys and secured to the carrier, and a plurality of tension springs in the chamber connected at one end with the pan and at the other end with the carrier, said springs exerting a force upon the carrier in a direction tending to take up the cables.

6. A bed structure adapted to be lowered from the ceiling of a bedroom for occupancy comprising a rectangular pan having a closed bottom chamber, a guideway in the chamber fixed to the bottom of the pan, a carrier in the chamber having a shoe slidably mounted in the guideway, a row of tension springs in the chamber connected with the pan at one end and with the carrier at the other end, said carrier traversing the guideway and having an equal number of springs connected thereto on each side of the guideway, cable guide means fixed in the corners of the pan chamber and in line with the carrier, and suspension cables having their upper ends adapted to be anchored to the bedroom ceiling and their lower ends extending around the guide means in the chamber and secured to the carrier, said carrier shoe having sufficient play in the guideway to shift into wedged relation therein upon breakage of any one of the springs.

7. A bed structure adapted to be lowered from the ceiling of a bedroom for occupancy comprising

ing a rectangular pan having a lower chamber, a sound deadening strip in the chamber extending lengthwise above the center of the pan bottom and fixed thereon, a guideway fixed on the strip, anchor means having a shoe slidable in the guideway, tension springs coated with sound deadening material having one end connected with an end of the pan and the other end connected with the anchor means, cable guide means fixed in the pan chamber, and suspension cables having their upper ends adapted to be anchored to the bedroom ceiling and their lower ends extending into the chamber and around the guide means and fixed to the anchor means, said springs exerting

a force upon said anchor means in a direction tending to take up the cables.
